UNITED STATES PATENT OFFICE.

HENRY JOHN FINLAY, OF NEW YORK, N. Y.

GAME APPARATUS.

No. 891,613.

Specification of Letters Patent.

Patented June 23, 1908.

Application filed December 9, 1907. Serial No. 405,795.

To all whom it may concern:

Be it known that I, HENRY JOHN FINLAY, a citizen of the United States, and a resident of the city of New York, borough of Manhattan, in the county and State of New York, have invented a new and Improved Game Apparatus, of which the following is a full, clear, and exact description.

The object of the invention is to provide a new and improved game apparatus, more especially designed for playing "stock exchange", and arranged to afford amusement to the players and onlookers, and to require considerable skill on the part of the players 15 to successfully play the game.

The invention consists of novel features and parts and combinations of the same, which will be more fully described herein-after and then pointed out in the claims.

20 A practical embodiment of the invention is represented in the accompanying drawings forming a part of this specification, in which similar characters of reference indicate corresponding parts in both views.

25 Figure 1 is a plan view of the improvement, and Fig. 2 is a central side elevation of the improvement on the line 2—2 of Fig. 1.

The board A of the game apparatus is provided at its bottom with a centrally-30 arranged depending pivot B, adapted to rest on a table C or other support, to permit the player having hold of the board to rock the latter in a desired direction, for a purpose hereinafter more fully explained.

35 On the top of the board A are arranged the marginal side pieces D, D' and the end pieces E, E', and from the said end pieces extend sets of partitions or bars F, F', parallel to the side pieces D, D', so that parallel stock passages G are formed on top of the board A. The partitions F, F' of each 40 set of partitions are spaced at their adjacent ends at or near the middle of the board A, whereby the stock passages G are connected with each other at the middle of the board by connecting passages G'.

The stock passages G are appropriately designated at the end piece E by headings, indicating the names of the stocks to be 50 dealt in, and the stock passages G are also marked "Cornered" at the end piece E marked "Receiver's hands" at the end piece E'. The stock passages G are ruled transversely and the lines are numbered at the side piece D' to indicate the value of the stocks, the numeral 100 or par value appearing at

the middle of the side piece D' opposite the transverse passages G'. The numerals are arranged in an ascending scale towards the end piece E and in a descending scale towards the end piece E', as plainly indicated in Fig. 1.

In playing the game use is made of pawns H, one for each stock passage G, and a ball I rolling on the top surface of the board A for 60 pushing the pawns H along the passages G towards either end piece E or E'. The game is played by two persons, one is termed the "bull" and the other the "bear", the "bull" player endeavoring to force the market, that 65 is, to push the pawns H in the passages G towards the end piece E, while the "bear" player endeavors to push the pawns H in the passages G towards the end piece E'. In starting the game the pawns H are placed in 70 central positions in the passages G opposite the connecting passages G', as plainly indicated in Fig. 1, and the ball I is placed in a recess D² formed in the side piece D at or near the middle thereof. The game may be 75 started by either player, recourse being had usually to drawing lots for first or second position. Now if the "bull" player wins, he takes hold of the board A at the corners of the end piece E' and then tilts the board A 80 upon the pivot B so that the ball I leaves the seat D² and rolls against the pawn H in the first passage G at the left-hand side, with a view to push this pawn H along the stock passage G towards the end piece E. 85 The player is allowed to hit this pawn H twice and then the board A is tilted, so that the ball I passes through the connecting passage G' into the second stock passage G, in which the above-described operation is 90 repeated, that is, the player tilts the board A to cause the ball I to strike the pawn H in the second stock passage G twice, with a view to move this pawn towards the end piece E. The above-described operation is repeated 95 100 for the several passages and pawns therein, and when the "bull" player has finished, the ball I is returned to the starting recess D², after which the "bear" player takes hold of the board A at the corners of the end piece E 105 and then rocks the board A to manipulate the ball I in such a manner as to strike each pawn H twice, and with a view to force the same in the corresponding passage G towards the end piece E'. The play in any 110 one of the passages G comes to an end in case the "bull" player succeeds in getting

the pawn H up against the end piece E, as the particular stock is then considered to have been cornered. In a like manner the play in a particular stock passage G comes to 5 an end in case the "bear" player succeeds in driving the corresponding pawn H to the end of the passage at the end piece E', as the stock is then considered to be in the receiver's hands.

10 As the positions of the pawns H in the passages G can be readily read by the ascending and descending scales at the side piece D', it is evident that the market value of the stock after the players are through can be readily 15 determined. Thus, if the "bull" player, for instance, corners three stocks, the "bear" player must pay the bull player 88 markers for each stock cornered. But should the three remaining stocks be below par, the "bear" 20 player naturally is paid with markers or credited to the extent of their market representation or value below par. In case the "bull" player hits a pawn H and then on the same roll of the ball I the latter strikes the 25 end piece E, or a "bear" player strikes the end piece E', then the pawn must be returned to the quotation it previously held, and the player then directs the ball I to the next following passage G, thus losing his turn to attack 30 the replaced pawn.

From the foregoing it will be seen that it is of great importance that the exact quotation of each pawn H should be carefully noted by the players before an attack is made, so that 35 no dispute may arise in returning the pawn to its previous position in case of a foul stroke, as above mentioned. If a player accidentally hits a pawn H three times in succession, it counts one point against the player on the 40 second chance at the next round.

Although I have described the use of the game apparatus for two opposite players, it is understood that a number of "bull" players and an equal number of "bear" players 45 may take turns in succession in playing the game.

Although I have outlined the way the game is to be played, it is evident that other rules may be used, if desired.

50 The game apparatus shown and described is very simple and durable in construction, affords amusement to the players and the onlookers, and requires considerable skill on the part of the players to successfully play 55 the game.

Having thus described my invention, I claim as new and desire to secure by Letters Patent:

1. A game apparatus comprising a board 60 having a depending central pivot adapted to rest on a table or other support, a plurality of passages arranged on the face of the board one alongside the other and appropriately designated to indicate stocks, the passages 65 being in communication with each other at

the middle thereof, and pawns mounted to slide on the said board along the passages in either direction from the middle thereof to mark the rise or fall of the particular stocks of the corresponding passages.

2. A game apparatus comprising a board 70 having a depending central pivot adapted to rest on a table or other support, a plurality of passages arranged on the face of the board one alongside the other and in communication with each other at the middle, the board being provided with headings for the passages, indicating the names of the stocks and with numerals indicating the value of the stocks, pawns mounted to slide on the said 75 board along the passages in either direction from the middle thereof to mark the rise or fall of the particular stocks of the corresponding passages.

3. A game apparatus comprising a board 80 having a depending central pivot adapted to rest on a table or other support, a plurality of passages arranged on the face of the board one alongside the other and appropriately 85 designated to indicate the names of the stocks, the passages being in communication with each other at the middle thereof, pawns mounted to slide on the said board along the 90 passages in either direction from the middle thereof to mark the rise or fall of the particular 95 stocks of the corresponding passages, and numerals on the board and indicating stock 100 quotations for the said passages, the numerals being arranged in ascending and descending directions from the middle of the passages.

4. A game apparatus comprising a board 105 having a depending central pivot adapted to rest on a table or other support, a plurality of passages arranged on the face of the board one alongside the other and appropriately 110 designated to indicate the names of the stocks, the passages being in communication with each other at the middle thereof, pawns mounted to slide on the said board along the 115 passages in either direction from the middle thereof, to mark the rise or fall of the particular stocks of the corresponding passages, numerals on the board and indicating stock 120 quotations for the said passages, the numerals being arranged in ascending and descending directions from the middle of the passages, and a ball adapted to roll on the said board for propelling the said pawns.

5. A game apparatus comprising a board 125 having a plurality of passages communicating with each other at the center of the board, the board being provided with headings for the passages, indicating the names of the stocks, and with numerals arranged in ascending and descending scales, indicating the 130 value of the stocks, and pawns adapted to be moved along the passages in either direction from the middle of the board, opposite the

numerals of the scales to indicate the rise or fall of the stocks.

6. A game apparatus comprising a board having a plurality of passages communicating with each other at the center of the board, the board being provided with headings for the passages, indicating the names of the stocks and with numerals arranged in ascending and descending scales for indicating 10 the value of the stocks, pawns adapted to be moved along the passages in either direction from the middle of the board, opposite the

numerals of the scales to indicate the rise or fall of the stocks, and a ball adapted to roll on the board by the tilting of the said board, 15 for propelling the pawns.

In testimony whereof I have signed my name to this specification in the presence of two subscribing witnesses.
